UNITED STATES PATENT OFFICE

HARRY R. FOWLER, OF TOLEDO, OHIO

TRAFFIC GATE

Application filed May 16, 1929. Serial No. 363,471.

This invention relates to movable traffic devices.

This invention has utility when incorporated in retractile driven arms and control means therefor, more particularly as to the arms being distortable for recovery to normal form.

Referring to the drawings:

Fig. 1 is a general plan view of an installation embodying the invention;

Fig. 2 is a fragmentary perspective view of a wrapping of one of the strips for the gate or arm;

Fig. 3 is a view of a standard from the high-way side with the cover removed;

Fig. 4 is a side elevation of the standard of Fig. 3 with the end cover removed;

Fig. 5 is a plan view of the standard with the cover removed;

Fig. 6 is a detail view of an adjustable guide for the strap as about the drum;

Fig. 7 is a detail view of the gate or arm free end in side elevation;

Fig. 8 is an end elevation of the arm or gate, and

Fig. 9 is a section on the line IX-IX, Fig. 5.

The movable traffic device may be connected up for directing a traffic control, and in the instance herein shown, it is associated on highway 1 as to railway 2, in such manner that an approaching train on the railway may operate remote control devices 3 for throwing the gate into guarding position as the train is approaching the highway 1, while as the train leaves the highway 1, remote control device 4 is operated for clearing the highway 1 of the traffic control device.

There is provided for the gate herein, standard 5 having therein power source as electric motor 6, shown as depending from cross arm 7.

This motor 6 is provided with shaft 8 co-acting through sprocket wheel 9 and sprocket chain 10 for driving sprocket wheel 11 on shaft 12 effective through worm 13 for driving worm wheel 14 on upright shaft 15 with which is fixed drums 16, 17. Also fixed on the shaft 15 is gear wheel 18 in mesh with gear 19 on shaft 20 carrying drums 21, 22,

similar to the drums 16, 17, whereby there is provided herein two pairs of opposing drums.

Fast on the shaft 20 is bevel pinion 23 in mesh with bevel pinion 24 on shaft 25 mounted in bearing 26 carried by cross arm 27 providing bearings 28, 29, for the shafts 15, 20. This shaft 25 has fast thereon pinion 30 in mesh with gear 31 on shaft 32 extending into time switch control box 33 effective upon the predetermined rotation of the drums for cutting out the motor 6 automatically.

At anchor 34 each drum 16, 17, 21, 22, has attached thereto, strip 35, which in its wraps about its drum is held in snug assembly in the coil relation by rollers 36 thrown by compression helical springs 37, the compression of which may be adjusted by bolts 38. In these wraps of the strips 35 about the drums there is a flat contour for these strips 35, notwithstanding the natural contour for the strips as clear of the winding and unwinding turns thereof, to have dished and concave portion 39 in the projected extent of these strips thereby contributing a sustaining degree of rigidity in the on-edge direction of such strips as off the drums.

The standard 5 is provided with enclosing side plates 40, 41, with cover 42. Through the side plate 41 as toward the highway 1 is port 43 (Fig. 9) through which the termini of the strips 35 may extend. The strips 35 (Fig. 7) have slots 44 therein for receiving anchor bolts 45 in assembling connecting block 46 between the termini of the two pairs of outwardly convex strips as disposed one strip above the other. This block 46 provides standard for signal light 47 having electric connections 48 thereto extending into the standard 5 over guide roller 49 to retrieving device 50 for this flexible conductor, which conductor is cut out by its switch 51 as the arms are fully retracted, due to the operation of arm 52.

In the operation hereunder, the throwing in of the motor 6 by the remote control at once starts an outward thrusting travel of the block 46 as carried by the four strips, say of spring sheet steel, with the strips from the transversely flat position on the drums to

transversely dished position as going through the port 43. In this transversely dished form, the convex sides are outward in the upper and lower pair of these strips. This movement brings the arm 52 to operate the switch 51 for forthwith lighting the signal 47 as a traffic warning, while the strips 35 in the assembled grouping move outward toward the central portion of the highway. This arm may be of such on-edge direction rigidity as to sustain the arm as a free end clear of the pavement, although, a leg device may be provided for support if such should be found desirable in more extensive installations.

Importance attaches to this disclosure in that it retains a normal gate intercepting position, with attribute of deformation in that should a vehicle be in the line of closing travel for the gates, the gates will continue their projection from the standards and buckle or weave as to such object, and at once the distortion is relieved by the vehicle shifting clear thereof, the gate is in the normal horizontal direction for a traffic warning and signal, with the strips marked in such conspicuous manner as may be approved for such traffic hazard minimizing, as diagonal bars of black and white of considerable width.

In the event the gates are in closed position and one loses control of a vehicle in approaching thereto, a similar lateral flexibility avoids wrecking of the gate or the standard so that as there is clear-way the gate may resume its position of projection or may even be retracted from a distorted position by the automatic controls or manually by removable crank 53 on shaft 12. The degree of resistance to lateral flexing may be determined by dishing; by the temper of the strips; and the gage of the material used. The material may be very light in the instances where visible signaling is more desired than impedance in a positive closure against highway traffic.

These features of flexibility in the direction of traffic, or with traffic hindrance, make possible a remote control automatic gate as practical against wrecking of equipment or injury to vehicles or hurtful to the flow of traffic, while adequate in its warning attributes.

Upon retraction of the gates, the mid-highway lights 47 are cut out by the switch device 51, 52. In practice, at once the motor 6 is cut in for projecting and until the light 47 is retracted, additional lights 54 are provided on the standards for directing transversely of the highway along the barred decorated strips for the gate, in thereby enhancing the visible signal effectiveness. Additionally, there may be audible alarm 55 cut in for directing vehicle operator's attention at all times that the strips are not fully retracted.

Additional holding, and guiding means

for the winding and unwinding of the strips 35 may be provided in the form of lubricating shoe 56.

Fender 57 may be provided at the terminus 46.

What is claimed and it is desired to secure by Letters Patent is:

1. A traffic gate embodying an on-edge strip of sheet material of sustaining degree of rigidity in the on-edge direction and in a recoverable degree of flexibility transversely, a standard providing a sheet material support, and a controllable material actuating device at the standard for propelling the material for travel in one direction as to the standard.

2. A traffic gate embodying a pair of terminally connected material strips disposed on-edge, one parallel to the other, for projection in having free ends, having an on-edge sustaining rigidity and transversely a recoverable flexing deformation, a sustaining standard for the strips, and a connection between said free ends of the strips, movable therewith toward and from the standard.

3. A traffic device embodying a standard, a horizontally projectable gate from the standard, said gate comprising an on-edge strip of a degree of sustaining rigidity from the standard and recoverable, from horizontal flexing as to the standard, and strip retracting and winding means at the standard operable for opening the gate.

4. A traffic device embodying a horizontally projectable gate, a standard therefor, said gate comprising a pair of parallel on-edge strips of a degree of sustaining rigidity from the standard in the on-edge direction and laterally flexible for recovery, and strip projecting and unwinding means in the standard operable for closing the gate.

5. A traffic gate comprising longitudinally-parallel transversely-concaved strips having adjacent free ends, and assembly means between said free ends.

6. A traffic gate comprising a pair of oppositely transversely-dished longitudinally-parallel strips having adjacent free ends, and assembly means between said free ends.

7. A traffic device comprising a standard, a horizontally projectable gate from the standard, said gate comprising a transversely concave strip.

8. A traffic device embodying a standard, a strip sheet material gate of arc cross-sectional form as projected, and strip material propulsion means for flattening and coiling the strip material of the gate in the standard.

9. A traffic device embodying a standard, winding and unwinding means in the standard, and a strip material gate of a sustaining degree of rigidity in the on-edge direction to be retracted into and extended from the standard by said winding and unwinding means.

10. A traffic device embodying a standard, winding and unwinding means in the standard, and a normally transversely concaved strip material gate to be retracted into and extended from said standard by said winding and unwinding means.

5 In witness whereof I affix my signature.
HARRY R. FOWLER.
